MINE CAR

Herman Henry Pancake, Huntington, W. Va., assignor to American Car and Foundry Company, New York, N. Y., a corporation of New Jersey

Application March 30, 1932, Serial No. 601,925

15 Claims. (Cl. 105—364)

This invention relates to mine cars and with regard to more specific features thereof to large capacity low lading-level mine cars.

The invention has for one of its objects to provide a light-weight but sturdy car particularly adapted to withstand the severe conditions of mine service; a car which will endure the shocks and strains of uneven road beds; which will support heavy material to full capacity lading and which is especially resistant to torsional strains at the points of union between the lading body and the axle pedestals.

Another object of the invention is to provide an inexpensive body construction largely of plate metal but having incorporated therewith or attached thereto certain strengthening and, or, reinforcing, elements so arranged as to obtain maximum body strength by a minimum of said elements.

Another object is in the provision of a certain type of longitudinal beam or sill used in conjunction with a plurality of transverse supporting belts or straps, in a manner of assembly which obtains suitable fit and engagement of parts heretofore difficult and expensive, if not actually impossible, to obtain.

Still another object is to provide a stub-axle assembly and mounting therewith, in alternative forms of solid roller, or Timken, bearings between the axle and wheel in which, when Timken or other conical roller bearings are used, an adjusting device of durable construction may be incorporated; the means for making the adjustment being easily accessible and operable without requiring special tools.

Other objects will be in part obvious and in part pointed out particularly hereinafter.

The invention accordingly consists in the various features of construction, arrangements of parts and combinations of elements which will be exemplified by the description hereinafter set forth and the scope of the application of which will be indicated in the appended claims.

In the drawings:

Figures 1 and 2 are complementary views in side elevation of a mine car embodying the invention.

Fig. 3 is a view in bottom plan of one half of the car as shown in Fig. 2.

Fig. 4 is a view in end elevation of the same.

Fig. 5 is a view in cross section taken through one of the stub axles.

Fig. 6 is a view corresponding to Fig. 5 but showing a modified form of the invention in which the anti-friction bearings between the wheel and the axle are of the solid roller type.

Referring more in detail to the drawings, spaced longitudinal members or side sills are indicated at 10. According to a preferred form of this invention these sills are inverted bulb angles positioned so that webs 11 thereof stand vertical and

flanges 12 project outwardly. At their ends these sills are connected to end sill members 13 by angle members 14. The end sills are preferably of metal plate having lower flanges 15 directed toward the car and upper flanges 16 extending 65 from the car and constituting draw-bar members suitably recessed as indicated at 17. Bumpers are attached to the end sills as indicated at 18 and 19.

The present invention is applicable to cars using the lift end gate for discharging, or to cars 70 of the rotary dump type. The drawings show a lift end gate 20 pivoted at 21 and by reason of the end gate construction the draw-bar and bumper mechanism at the gate end of the car is slightly different from the construction just described 75 which is at the fixed wall end of the car. These differences in detail are not considered important to an understanding of the present invention.

The side sills are also connected by a central lading bottom 22 preferably of plate metal and 80 having flanges 23 at either side which match with the lower portions of the sills and are secured thereto so as to bring the flooring proper in line with the bulb edges of the sills.

Side lading bottoms constituted by flare sheets 85 24 are riveted to the top flanges 12 of the sills and side walls 25 extend upwardly from the outer edges of the side lading bottoms either as a part thereof or as separate pieces suitably joined therewith. The car shown in the drawings has 90 a fixed end wall 26 of plate metal and a movable end gate 20 as previously described. In rotary dump car construction an end wall similar to 26 is applied at the opposite end of the car. In cars for end dumping operation a slope sheet 27 is 95 applied to the central lading bottom at the dump end of the car so as to facilitate the discharge of the lading. Obviously this is omitted in rotary dump car construction.

The car body including the side walls and side 100 lading bottoms, constituting the wings, and the sills and central lading bottom, is reinforced by a series of spaced transverse belts or straps certain of which, as indicated at 30, are intermediate straps which pass entirely around the body from 105 the top of one side wall to the top of the opposite side wall. Other belts 31 preferably extend from the tops of the side walls along the under-face of the side lading bottoms and down against the outer faces of the webs of the side sills. At the gate 110 end of the body a transverse belt 32 passes from the top of one side wall around the body to the top of the opposite side wall. The belts 30 and the end belt 32 are riveted at intervals along the side walls and to a certain extent under the side 115 lading bottoms and then descend obliquely as indicated at 33 and are formed around the bulb edges of the sills as shown clearly at 34 in Fig. 5. Preferably, they are riveted along the central lading bottom and it will be noted that the bulb 120

edge provides a convenient means for making a close fit of the belts. It will also be noted that no fillers are required between the belts and the central lading bottom. The belts with diagonal reaches from the side lading bottoms to the central lading bottom give the effect of a reinforcing gusset or strut for the side wings while the belts or straps 31 having their lower ends riveted to the sills and their reaches riveted to the side lading bottoms and the side walls, reinforce and maintain the wings by direct association with the substantial sill members.

The car shown in the drawings is supported at four zones, two at each of the opposite sides of the car directly under the lading wings, and each of the supports comprises a construction in which a four-point support is effected due to the specific construction and arrangement of parts as now to be described. Secured to the outer surfaces of the webs of the side sills 10 by rivets 42, or other suitable fasteners, are inner axle bearings 40, castings in the instance shown, which are fitted between the flanges 12 and the bulbs of the sills 10, as clearly shown in Figs. 5 and 6. The bearings 40 are apertured to receive the enlarged inner ends 51 of stub axles 50; the apertures being of such form as to permit a clearance 40' between the axle and bearings 40 to compensate for irregularities and unevenness of track grades without imposing undue strains on the car.

The axles 50 are mounted in wheels 60 and the outer end portions 52 thereof are positioned in the central portions or bearing portions 41' of the outer axle bearings 41, the central portions 41' being provided with apertures of such shape as to provide a clearance 52'.

The outer axle bearings 41 are elongated castings and each includes arms 45 extending in opposite directions from the central portion 41' and having their end portions underlying successive belts 30 and 31 and provided with attaching flanges 46 which receive bolts 70 extending through the flanges 65 of wheel housings 61 covering the wheels 60; the wheels extending into openings formed in the side lading bottoms of the car. The housings 61 are also formed with flanges 62 secured to the side walls 25 of the body by rivets 63 and with attaching flanges 64 connected to the flanges 12 of the side sills by the rivets 43. At points other than those which take the bolts 70, the wheel housings are secured to the side lading bottoms by rivets 71, as shown clearly in Fig. 3.

Thus the curved wheel hood and longitudinally extending outer axle bearing 41, the straps 30 and 31 and the body pieces are tied into an integral and strongly reinforced structure. Not only are the metal plate lading bottoms and side walls strengthened but the strengthening means are tied into the sills by the engagement of the straps 31 with the webs of the sills and the engagement of the wheel hoods with the flanges of the sills.

If the wheeled axle is of the solid roller type as shown in Fig. 6 the wheel hub 80 may be extended as shown at 81 owing to the spacing between the axle bearings. A cotter pin 82 is introduced through apertures 83 in the extended hub and cooperates with a flange 84 through the intermediary of a washer 85 to limit relative lateral movement of the wheel and axle. The hub may be filled with lubricant through apertures 83 which are suitably plugged when filled. The rollers are indicated at 86.

Where cone bearings are used as shown in Fig.

5 of the drawings the axle is held in position by an end flange 90 engaging a shoulder 91 of the inner axle bearing. A collar 92 is fixed on the axle adjacent the inner axle bearing and a collar 93 is loose on the axle toward the outer end. Between the collar 93 and the axle bearing 41 an adjusting nut is threaded on a reduced end of the axle so that by rotation thereof the loose collar 93 may be moved toward the fixed collar 92 bringing together spaced bearing races mounted on the axle. Cooperating spaced bearing races are adjusted in the hub of the wheel 60 and conical rollers are arranged between the races. It will be noted that the adjusting nut is protected to a degree by the outer axle bearing casting but is exposed, nevertheless, in position where it may be operated by an ordinary wrench. No sleeves are required between the nut and loose collar which eliminates an objection to prior constructions.

Heavily laden mine cars throw exceptional torsional strains onto the connections between the axle assemblies and the body, particularly in going around curves. The flanges of the wheels cause the axles to conform to the curvature of the tracks while the tendency of the heavily laden body is to continue in the direction it was going. The present invention comprises a simple and relatively inexpensive arrangement of parts admirably suited to the withstanding of such strains and to the other strains and stresses incident to the loading, unloading and carrying of heavy materials.

It will also be obvious that the present construction provides for supporting the car body 110 by spaced pairs of axle bearings supported by stub axles, the outer bearings being arranged beneath the side lading bottoms or side floor portions of the car body and being connected to the latter at widely spaced points, this arrangement in cooperation with the inner and outer bearing members providing for a four-point support at four zones of the car body. More specifically, the outer axle bearings are connected to the body through body stiffening elements in the form of 120 belts, certain of which extend down the sides of the car and under the central lading bottom while others extend down the car sides and terminate at and are connected to the body side sills. Each of the stiffening elements underlies the side lading bottoms, as clearly shown in the drawings.

The drawings herein illustrate one embodiment of the invention but it is to be understood that they are for illustrative purposes only and various changes in the form and proportions of the construction may be made within the scope of the appended claims without departing from the spirit of the invention.

What is claimed is:

1. In a mine car, in combination, a lading body comprising an underframe having spaced longitudinal members, spaced transverse belts fixed to the body, and spaced axle bearings arranged in pairs on opposite sides of the body, one of the bearings of each pair being spaced outwardly relative to the body members and having its ends secured to the belts, and the other bearing of the pair being secured to one of the said longitudinal members.

2. In a mine car, in combination, a lading body comprising an underframe having spaced longitudinally arranged inverted bulb angles with the flanges thereof extending outwardly, spaced transverse belts fixed to the body and formed around the bulbs of said bulb angles, and spaced

- axle bearings arranged in pairs on opposite sides of the body and outwardly relative to the bulb angles, one of the bearings of each pair extending longitudinally and having its ends secured to the belts and the other bearings of said pairs being secured to the bulb angles.
3. In a mine car, in combination, a lading body comprising an underframe having spaced longitudinally arranged inverted bulb angles with the flanges thereof extending outwardly, spaced transverse belts fixed to the body and formed around the bulbs of said bulb angles, and spaced axle bearings arranged in pairs on opposite sides of the body and outwardly relative to the bulb angles, one of the bearings of each pair being of elongated form and having its ends secured to adjacently arranged belts, and the other axle bearing of the pair being secured to the web and flange of one of said bulb angles.
- 20 4. In a mine car, side sills comprising bulb angles inverted and having their flanges extending outwardly, side wings secured to the flanges, and a central lading bottom having side flanges secured to the sills, spaced transverse belts secured to the side wings and central lading bottom and formed around the bulb edge of said sills, and spaced bearing members for stub axles comprising outer castings extending parallel to the sills and secured to the belts.
- 25 5. In a mine car, side sills comprising bulb angles inverted and having their flanges extending outwardly, side wings secured to the flanges, and a central lading bottom having side flanges secured to the sills, spaced transverse belts secured to the side wings and central lading bottom and formed around the bulb edge of said sills, and spaced bearing members for stub axles comprising outer castings extending parallel to the sills and secured to the belts and inner castings secured to the webs of the sills.
- 40 6. In a mine car, side sills comprising inverted bulb angles, a central lading bottom between the lower portions of the sills, side wings comprising side walls and side lading bottoms secured to the sills, and spaced transverse belts secured to the side walls, the side lading bottoms and the central lading bottom, wheeled stub axles, pairs of spaced axle bearings on opposite sides of the car, one of each pair being of elongated form and having its ends joining with the spaced belts.
- 45 7. In a mine car, side sills comprising inverted bulb angles, a central lading bottom between the lower portions of the sills, side wings comprising side walls and side lading bottoms secured to the sills, and spaced transverse belts secured to the side walls, the side lading bottoms and the central lading bottom, wheeled stub axles, pairs of spaced axle bearings on opposite sides of the car, one of each pair extending from one of said belts to another, and wheel hoods covering apertures in the side lading bottoms, said wheel hoods, said axle bearing ends and said spaced belts being matched and secured to the side lading bottom by means common to them all.
- 50 8. In a stub axle mine car, a body having side walls and side and central lading bottoms arranged respectively in different horizontal planes, body stiffening elements secured to the side walls and underlying the side lading bottoms, and means for supporting the body comprising a pair of independent axle bearings secured to the body, one thereof having a central bearing portion and arms projecting in opposite directions there-
- from and attached to adjacent body stiffening elements.
9. In a stub axle mine car, a body having side walls and side and central lading bottoms arranged respectively in different horizontal planes, body stiffening elements secured to the side walls and underlying the side lading bottoms, and means for supporting the body comprising a pair of independent axle bearings secured to the body, one thereof underlying the side lading bottom and having its ends connected to the underlying portions of adjacent body stiffening elements.
10. In a stub axle mine car, a body including a side sill, a side wall and central and side lading bottoms, an inner axle bearing secured to the side sill and an elongated outer axle bearing underlying the side lading bottoms and having its end portions connected to said side lading bottoms at widely separated points whereby to cooperate with the inner and outer axle bearings in constituting a four-point support for said body.
- 15 11. In a mine car, a body having side walls, body side sills and a lading supporting bottom, belts secured to the side walls and underlying the bottom, stub axles, and oppositely arranged pairs of inner and outer axle bearing members spaced longitudinally of the car for supporting the body, said inner members being secured to the side sills and said outer members extending between and being connected to adjacent belts.
- 20 12. In a mine car, a body comprising side sills, side walls, a central lading supporting bottom extending between and connected to the lower portions of the side sills, side lading bottoms between the side walls and the upper portions of said side sills, belts arranged in spaced relation and underlying the side lading bottoms, stub axles arranged in a plane above the central lading bottom, inner axle bearings secured to the side sills, and outer axle bearings extending between adjacent belts and connected thereto.
- 25 13. In a mine car, a body including a lading supporting bottom, body side sills, and ties between said sills, stub axles, and pairs of independent inner and outer axle bearings spaced longitudinally of the body, said inner axle bearings being secured to the body side sills and the outer bearings each being secured to at least one of the ties.
- 30 14. In a mine car, a body having side walls, body side sills and a lading supporting bottom, belts secured to the side sills and underlying the bottom, stub axles, and pairs of inner and outer axle bearing members for supporting the body and in which said stub axles are arranged, said bearing members being arranged in longitudinally spaced relation with respect to the body with the inner bearing members secured to the side sills and the outer bearing members underlying the car bottom and extending between and connected to adjacent belts.
- 35 15. In a mine car, in combination, a lading body comprising an underframe having spaced longitudinal body members, spaced belts secured to the body and extending down the sides and under the bottom of said body, and spaced axle bearings arranged in pairs on opposite sides of the body and outwardly of the longitudinal members, one of the bearings of each pair being so formed as to extend between and be secured to adjacent belts and the other bearing of each pair being secured to one of the said longitudinal members.

HERMAN HENRY PANCAKE.
